MANUFACTURE OF CIGARS

Constantin Friedrich Röber, Dresden, Germany,
assignor to "Universelle" Cigarettenmaschinen-
fabrik J. C. Mueller & Co., Dresden, Germany

Application March 18, 1936, Serial No. 69,443
In Germany March 21, 1935

9 Claims. (Cl. 131—49)

This invention relates to the manufacture of cigars by machinery, and more particularly to the manufacture and application of the outer wrapper.

5 An object of this invention is to provide a device which may be used with a wrapping machine which initially cuts the wrapper into the desired shape and then applies an adhesive to at least one end of the wrapper as it is being fed to the 10 wrapping machine.

Another object of this invention is to provide an improved type of wrapper which is so constructed that it will smoothly engage the filler and which embodies a construction which will 15 permit the smooth application of the wrapper at the mouth end of the cigar irrespective of whether or not the wrapper is initially started at the proper point with respect to the filler.

A further object of this invention is to provide 20 a device which is adapted to stamp out the wrapper in the desired shape and then transfer the shaped wrapper to the wrapping machine, at least one end of the wrapper being supported for engagement with an adhesive applying means so 25 that the "flag" end of the wrapper will be securely held about the filler.

With the foregoing and other objects in view, the invention will be more fully described herein-after and will be more particularly pointed out 30 in the claims appended hereto.

In the drawings, wherein like symbols refer to like or corresponding parts throughout the several views:

Figure 1 is a plan view of a wrapper with a 35 conventional slit at the flag end.

Figure 2 is a plan view of a wrapper constructed according to an embodiment of this invention.

Figure 3 is a plan view of a modified form of wrapper.

40 Figure 4 is a fragmentary plan view, partly diagrammatic, of a wrapper cutting and applying machine constructed according to an embodiment of this invention.

Figure 5 is a sectional view taken on the line 45 5—5 of Fig. 4.

Figure 6 is a sectional view taken on the line 6—6 of Fig. 4.

Figure 7 is an enlarged vertical section of the punch.

50 Figure 8 is a sectional view taken on the line 8—8 of Fig. 4.

Figure 9 is a fragmentary end elevation of the wrapping machine and including the adhesive applying means shown in Fig. 8.

55 Referring to the drawings, and first to Fig. 1,

the letter *a* designates generally the body of an elongated wrapper having an angularly related flag end *b* which is semicircular as shown, and which is provided with a radial slit *c*. The idea of using a slit such as the slit *c* will work satisfactorily where the filler is placed on the filler wrapping means with precision, but as there is frequently a variance in the disposition of the filler on the filler wrapping means, where a wrapper is used similar to that shown in Fig. 1 the flag end of the wrapper usually becomes very much distorted and folds appear at the mouth end of the cigar. The wrapper for the cigar is usually moist and on account of this condition the wrapper will more readily become distorted during the wrapping operation, and as a slight variance frequently occurs in the initial application of the wrapper, a wrapper of the type shown in Fig. 1 is not conducive to a smoothly wrapped cigar.

In Figure 2 there is shown a wrapper of substantially the same configuration as the wrapper shown in Fig. 1, but having a different shaped incision than that shown in Fig. 1. In Fig. 2 a central round hole *d* is provided, and from this two diverging cut outs form with the round hole a slot *c'*, as shown in Fig. 2. These diverging incisions form a trapezoidal portion, and this trapezoidal portion forms with the circular portion *d* of the round hole the slot *c'*. The use of a wrapper of this type will allow for any slight variations in the initial application of the wrapper to the filler by reason of the misplacement of the filler with respect to the wrapping means.

The wrapper *a''* shown in Figure 3 is somewhat similar to the wrapper shown in Fig. 2, except that the flag portion *b''* thereof is provided with a slot *e* having parallel sides and ending in a rounded inner end about the axis of the flag *b''*.

The material from which the wrapper *a'*, or the wrapper *a''* is made is passed over a table 2 which is provided with a knife 4 having the configuration of the wrapper *a'*, and inside the knife 4 a suction head 3 is provided for retaining the formed wrapper on the table 2 while the waste material is being removed.

Having initially formed the wrapper *a'* without the slot or hole in the flag end thereof, the wrapper *a'* is removed from the table 2 by means of a carrier 21 which is connected to a source of air suction. The carrier 21 is mounted on a standard or base for horizontal swinging movement, and at the time that the carrier 21 is in position to pick up the formed wrapper *a'*, the suction to the head 3 is cut off, or it may be re-

versed so as to forcibly discharge the formed wrapper onto the under side of the carrier 21.

When the wrapper *a'* has been picked up by the carrier 21, the carrier is then swung to the left as viewed in Fig. 4 and as indicated by the dot and dash lines *v*. The flag end *b'* of the wrapper *a'* is positioned with the center thereof directly above a punching member 5 which is secured to an arm 6 carried by the upper end of a vertically movable shaft 8. The arm 6 has a split eye portion 6' which is detachably clamped onto the reduced upper end of the shaft 8 by means of a screw 7. As shown in Figs. 5 and 6, the shaft 8 is slidable in a guide 9 carried by a base G, and an outstanding pin 10 is secured to the shaft 8 intermediate the ends thereof and above the top of the guide 9. The forked end 11 of a lever 12 engages the pin 10, and the opposite end of the lever 12 is mounted on a pivot 13 carried by a bracket arm 14 which is fixed to the guide 9.

A drive shaft 20 is rotatably supported on bearings 20' carried by the base G, and this shaft 20 has a punch lifting member 16 secured thereto which has a lifting cam 22 at one portion thereof. The lever 12 has a roller 15 on the lower side thereof which is adapted to engage the periphery of the lifting member and the cam 22. The roller 15 is maintained in contacting relation with the lifting member 16 by means of a spring 18, one end of which is secured to a pin 17 carried by the lever 12, and the other end of which is secured to a pin 19 carried by the guide 9. The major portion of the lifting member 16 is disposed concentric to the axis of the shaft 20 so that during this cycle of the lifting member 16 the shaft 8 carrying the punch 5 will remain stationary, and when the roller 15 is engaged by the cam portion 22 the lever 12 is raised and the shaft 8 with the punch 5 is also raised.

The under side of the carrier 21 may be provided with a cushion 23 against which the upper end of the punch 5 may engage. The punch 5 is hollow, and as shown in Fig. 7 the interior is downwardly flared so that the cuttings of the wrapper may easily fall downwardly, or if desired a suitable suction means may be attached to the lower end of the punch 5 so that the cuttings may be carried by such suction means to a suitable point of discharge. In horizontal section the shape of the punch 5 is similar to the tapered slot *c'* and the opening *d*, shown in Fig. 2.

After the flag end *b'* has been properly slotted by the punch 5, the carrier 21 is moved, as by swinging, to the position shown at *w* in Fig. 4. In this position the end of the wrapper *a'* which engages the outer end of the filler is disposed in a position directly above the filler Z which is mounted between rollers 1. Also, as shown in Fig. 4, the direction of movement of the wrapper is shown by the arrows *x* and *y*. The other or flag end of the wrapper *a'* is disposed above an adhesive applying roller 24 which is mounted on a shaft 25. The shaft 25 is mounted on one arm of a bell crank 26, and a roller 30 is mounted on the end of the other arm of the bell crank 26. The roller 30 engages a cam 31 which is secured to the shaft 20 so that when the carrier is in adhesive applying position the roller 24 will engage the under side of the wrapper.

An adhesive transfer roller 29 which is mounted on a shaft 27 is partially submerged in a reservoir 28 which is adapted to have a suitable adhesive disposed therein. A driving gear 32 is secured to the drive shaft 20 and engages a driving gear 33 mounted on a shaft 34, and a gear

train including the gears 33, 36, 37 and 40 will rotate the transfer roller 29 and also rotate the adhesive applying roller 24, the latter roller being rotated at substantially the same speed as the linear movement of the wrapper *a'* about the filler Z. The roller 24 also rotates in the direction of the movement of the wrapper as it is being wrapped about the filler Z so that the roller 24 will not effect any distortion of the shape or size of the wrapper *a'*.

In the use and operation of this device, the blank wrapper is initially stretched across the table 2 and over the forming knife 4. A roller or other pressure means is then applied to the upper surface of the blank wrapper so as to cut out the wrapper which is then held in position by the suction device 3. When the wrapper has been properly shaped as to its marginal configuration, the carrier 21 is brought into overlying position to the head 3 of the table 2, and at this time the suction of the head 3 is cut off, or if desired the suction may be reversed so as to eject the formed wrapper from the cutter 4. The suction in the head 21 will retain the formed wrapper on the underside thereof, and then the head 21 may be swung to the punching position where the cushion 23 will overlie the punch 5. At this time the cam 22 will be disposed in a position to engage the roller 15 and thus raise the lever 12 together with the shaft 8 and the punch 5.

The punching operation is performed quickly, and then the carrier 21 is moved to the adhesive applying position, and at this time the suction of the carrier 21 may be cut off so that the outer end of the wrapper *a'* will engage the filler Z. As soon as the carrier 21 is in adhesive applying position, the cam 31 will be so disposed that the lower end of the bell crank 26 will swing in the direction of the shaft 20 and thus carry the upper end thereof upwardly toward the overlying carrier 21. The adhesive applying roller 24 is secured to the upper end of the bell crank 26 so that when the upper portion of this bell crank rises the roller 24 will come into contact with the underside of the wrapper *a'*. Only the inner or flag end of the wrapper *a'* is engaged by the roller 24.

It is of course understood that various changes and modifications may be made in the details of construction of the above specifically described embodiment of this invention, such changes and modifications being limited only by the scope of the appended claims.

What is claimed is:

1. In a cigar making machine, means for shaping the wrapper, conveying means for conveying the wrapper from the shaping means, a flag slotting means disposed in the path of the movement of the wrapper by said conveying means, timed means for moving said slotting means to an operative position when the wrapper is disposed above said slotting means, and an adhesive applying means also disposed in the path of the movement of said conveying means and adapted to engage the flag end of the wrapper.

2. In a cigar making machine, means for shaping the wrapper, a slotting means for the flag end of the wrapper, suction means for conveying the shaped wrapper to a position for engagement with said slotting means, and means for applying an adhesive to the flag end of the wrapper.

3. In a cigar making machine, means for shaping the wrapper, a slotting means for the flag end of the wrapper, movable suction means for conveying the shaped wrapper to a position for

engagement with said slotting means, an adhesive applying means disposed in the path of the movement of said suction means, and timed means for moving said applying means to operative position.

- 5 4. In a cigar making machine, means for shaping the wrapper, a slotting means for the flag end of the wrapper, means for mounting said slotting means for movement to an operative or an inoperative position, wrapper carries means for conveying the wrapper from the shaping means to said slotting means, means active when said carrier is in a position overlying said slotting means for moving said slotting means to operative position, 10 an adhesive applying means disposed in the path of movement of said carrier, and means active when said carrier is in a position overlying said adhesive applying means for moving said adhesive applying means to operative position.
- 15 5. In a cigar making apparatus, having a wrapper cutting device, a filler holding device, and means for moving the cut wrapper from the wrapper cutting device to the filler holding device, said wrapper having a flag portion, the combination therewith of a punching device for punching an incision in the flag portion of the wrapper before the wrapper is moved from the cutting device to the filler holding device.

- 20 6. In a cigar making apparatus, a wrapper including a flag portion, a wrapper cutting device, a filler holding device, and means for moving the cut wrapper from the wrapper cutting device to the filler holding device, the combination therewith of a punching device for punching an 25 incision in the flag portion of said wrapper before the wrapper is moved from the cutting device to the filler holding device, and a counter support for the punching device, said punching device and counter support cooperating to act on the 30 wrapper when the wrapper moving means assumes a position of rest prior to the wrapper being supplied to the filler holding device.

- 35 7. In a cigar making apparatus having a wrapper including a flag portion, a wrapper cutting device, a filler holding device, and means for moving the cut wrapper from the wrapper device to the filler holding device, the combination therewith of a punching device for punching an incision in the flag portion of the wrapper before the wrapper is moved from the cutting device to the filler holding device, and an adhesive supplying device consisting of a horizontally supported roller adapted to be moved against the 40 wrapper flag from below the same, the axis of the 45

roller being at right angles to the direction of motion of the wrapper moving means.

8. In a cigar making apparatus, having a wrapper with a flag portion, a wrapper cutting device, a filler holding device, and means for moving the cut wrapper from the wrapper cutting device to the filler holding device, the combination therewith of a punching device for punching an incision in the flag portion of the wrapper before the wrapper is moved from the cutting 5 device to the filler holding device, and an adhesive supplying device consisting of a horizontally supported roller adapted to be moved against the wrapper flag from below the same, the axis of the roller being at right angles to the direction of motion of the wrapper moving means, said adhesive supplying device having a container for holding adhesive, a transfer roller operating therein, bearings for supporting the first named adhesive roller, a lever for supporting said bearings, means for swinging said lever around the shaft of the transfer roller, and a cam for controlling the movement of said lever for moving the first named adhesive against the 10 wrapper flag when the latter is situated above it.

15 9. In a cigar making apparatus, having a wrapper part of which includes a flag portion, a wrapper cutting device, a filler holding device, and means for moving the cut wrapper from the wrapper cutting device to the filler holding device, the combination therewith of a punching device for punching an incision in the flag portion of the wrapper before the wrapper is moved from the cutting device to the filler holding device, and an adhesive supplying device consisting of a horizontally supported roller adapted to be moving against the wrapper flag from below the same, the axis of the roller being at right angles to the direction of motion of the wrapper moving means, said adhesive supplying device having a container for holding adhesive, a transfer roller operating therein, bearings for supporting the first named adhesive roller, a lever for supporting said bearings, means for swinging said lever around the shaft of the transfer roller, a 20 cam for controlling the movement of said lever for moving the first named adhesive roller against the wrapper flag when the latter is situated above it, and means connected with the driving mechanism of the machine for moving the first named adhesive roller to a peripheral speed equal to the speed of movement of the 25 wrapper moving means.

CONSTANTIN FRIEDRICH RÖBER.
